REFRIGERATING APPARATUS

Ralph W. Doeg, Detroit, Mich., assignor to Nash-Kelvinator Corporation, Detroit, Mich., a corporation of Maryland

Application January 25, 1938, Serial No. 186,860

6 Claims. (Cl. 230—147)

This invention relates to a refrigerating apparatus, and more particularly to compressing units for use in connection with refrigerating apparatus.

5 An object of the invention is to provide an improved lubricating system for the moving parts of the compressor and in which the vane or blade of the piston acts as a pump for delivering the lubricant through the piston to the drive shaft 10 and its bearings for the purpose of lubricating the various operating parts.

Another object of my invention is to provide an improved arrangement for sealing the high pressure from the low pressure side of the compressing mechanism.

The invention consists of certain novel features of construction and combinations of parts which will be hereinafter described and pointed out in the claims.

20 In the accompanying drawings:

Fig. 1 is a view in elevation showing a refrigerating system embodying the invention;

Fig. 2 is a sectional view on the line 2—2 of Fig. 1;

25 Fig. 3 is a sectional view on the line 3—3 of Fig. 2;

Fig. 4 is a detailed sectional view showing the position of the piston, eccentric, vane and rocker members in a different position from that disclosed in Fig. 3;

30 Fig. 5 is a sectional view taken on the line 5—5 of Fig. 3;

Fig. 6 is a sectional view on the line 6—6 of Fig. 3 showing the valve in elevation;

35 Fig. 7 is a detailed vertical sectional view showing the relationship between the crank shaft, piston and vane; and

Fig. 8 is a detailed sectional view of a discharge valve.

40 Referring to the drawings the numeral 10 designates, in general, the compressor unit which withdraws evaporated refrigerant from a refrigerant evaporator 12 through a vapor conduit 13, compresses the evaporated refrigerant and delivers the same to a condenser 14, wherein it is liquefied and from which it is delivered to a high side float mechanism 15. The float mechanism controls the flow of liquid refrigerant to the evaporating element 12. The compressor is 45 driven by a motor 16 through a belt 17 traveling over a pulley 11 on the compressor. The operation of the motor 16 and compressor 10 is controlled by a thermostatic switch 18.

50 The compressor unit comprises, in general, a casing which is formed preferably in three sec-

tions; namely, a central section 20, and end sections 21 and 22. The central section is provided with a tubular shaped bearing 23 in which a driving shaft 24 is journaled. The central section 20 is provided with a vertical web or partition 28, and formed between this partition and the end section 22 is a lubricant chamber 29. The end section 21 is constructed in the form of a bell and is attached to the central section 20 by bolts 26, and provides a high pressure compartment 25 and housing for a rotary pump compressor.

5 The compressor is of the rotary type and consists of a cylinder block or casting 30 securely fastened to the partition or web 28 between an end plate 32 and one side of the partition, by means of bolts 33. The cylinder block or casting 30 has a cylindrical bore or compression chamber 31 in which there is disposed a rotary piston 34 mounted upon an eccentric 35 formed 10 on the crank or drive shaft 24. A blade or vane 36 is formed or connected to the piston 34.

15 The blade 36 reciprocates between two semi-circular rocker members 37, which are mounted to oscillate in a cylindrical recess 38 provided 20 in the cylinder casting 30. The blade is provided with a transverse slot 39 along its lower edge for the reception of a coiled spring 40 (Figs. 4 and 7), the ends of which are adapted 25 to be seated in depressions 41 in the flat faces of 30 the rocker members 37. The spring 40 spreads the rocker members at the bottom of said members to prevent pinching or binding the blade or vane and at the same time affords provision for increasing the sealing pressure at their upper 35 ends with the blade and the wall of the cylindrical recess 38 to insure sealing the high pressure side of the compressor from the low pressure side. An opening 44 is provided in the wall 40 between chamber 31 and the recess 38 through 40 which the blade 36 extends into the recess 38 and between the rocker members 37.

45 The cylindrical recess 38 communicates with a longitudinal groove 42 formed in the cylinder casting 30 and extending along the base of the recess 38 for forming an oil port therefor and disposed laterally of the vertical axis of said piston blade 36. A duct 43 is formed through the cylinder casting for supplying oil from the compartment 25 to the groove 42 and recess 38.

50 During the operation of the compressor, the pumping action withdraws the vaporized refrigerant from the evaporator 12 through the vapor conduit 13, whence it passes through an inlet opening 45 formed in the end section 21 into the 55

filtering chamber 46, through the filtering screen 50 into the passageway 47, formed in the end section 28, to the check valve 48, and from the check valve through the passageway and intake duct 49 formed in the casting 30, delivering the gaseous refrigerant to the compression chamber 31.

As the vaporized refrigerant is delivered to the compression chamber 31 through the port 49, the refrigerant will be compressed by the piston 34 through the rotation of the shaft 24, and the eccentric 35, which latter will cause the piston to move in a counter-clockwise direction in the chamber 31. The compressed refrigerant is discharged from the chamber through an outlet port 51, located in the wall of the chamber 31, and on the opposite side of the vane or blade 36, from the duct 49. A suitable check or reed valve 52 is mounted in the recess 54 of the end plate 32, and communicates through the passage 55, for controlling the discharge of the compressed refrigerant through the port 51 into the chamber 56 formed within the bell shaped housing 71 secured by bolts 72 to the face of the end plate 32. The valve 52 acts to prevent any back flow of the compressor refrigerant into the compression chamber 31. The compressed refrigerant is discharged, with any oil that may be in chamber 56, through the tube 73 into the high pressure compartment 25. Outlet opening 95 is placed high in the compartment 25 so as to entrap the oil in the compartment permitting only the compressed refrigerant to pass therethrough for delivery to the condenser 14.

In the operation of the lubricating system the compressor compartment 25 is, for example, filled to the height 105 with a body of lubricating medium. The shaft 24 is provided axially thereof with an oil passage 58 and a plurality of radial passages 59 communicating with said longitudinal or axial passage 58. These radial passages 59 have communication with annular grooves 60 formed around the shaft 24 for delivering the lubricant to the bearing in the tubular portion 23 and the bearing of the end plate 32.

The blade 36 and the piston 34 are provided with an oil passage 66 for conducting the oil to a semi-circular groove 67 formed on the outer surface of the eccentric 35. A transverse passage 68 formed in the eccentric and shaft 24 leads from one end of the semi-circular groove 67 through to the axial passage 58 of the shaft 24, to the opposite end of the semi-circular groove 67. The movement of the piston 34 in the compression of the refrigerant in the chamber 31 reciprocates and oscillates the blade 36 within the cylindrical recess 38 of the cylinder casting 30 and between the rocker members 37. As the rocker members 37 are oscillated by the piston 34 and vane or blade 36 in the recess 38, an edge of one of the rocker members will pass back and forth across the port or groove 42 and the rocker member will serve as a valve for cutting off the supply of oil to the recess 38. The piston 34 and blade 36 will function as a pump when the port 42 is closed, causing the oil collected between the rocker members and within the passage 66 of the blade 36 to be delivered up through the passage 66 to the semi-circular groove 67 of the eccentric, and thence through the transverse passage 68 of the axial passage 58 of the shaft 24. The oil will be forced through the axial and its radial passages to the various bearings throughout the length of the shaft.

This is accomplished by the travel of the piston

34 within the cylinder. Upon the up stroke of the piston, a portion of the lubricant medium is drawn in through the port 43 into the groove 42, and up into the recess 38. When the blade 36 makes its down stroke, Fig. 4, the lubricant in the recess 38 has been cut off from the supply in the compressor compartment 25 by a rocker member 37 closing or cutting off communication between the groove 42 and the recess 38, and the lubricant is forced upwardly through the passage 66 in the blade 36 and piston 34 to the groove 67 in the face of the eccentric 35. As the eccentric 35 continues to be rotated and the semi-circular groove 67 thereof passes out of communication with the passageway 66 of the blade and piston, the lubricant contained in the transverse passage 68 and groove 67 will drain into the axial passage 58 of the shaft 24.

The travel of the piston 34 counter-clockwise in the chamber 31 causes the blade 36 to be moved up and down between the two semi-circular rockers 37. As shown in Fig. 3, the blade has begun to move upwardly and is now drawing oil by suction through the duct 43 and port 42 into the recess 38 and as the piston continues to move, the blade is elevated, causing the rockers to be oscillated until one of the rocker members will pass over the port 42 and cut off communication from the lubricant in the high pressure compartment with the cylinder recess 38, so that on the down stroke of the piston this confined lubricant will be forced upwardly through the passage 66 in the blade 37. Of course, in this downward movement of the piston the rocker members 37 are oscillated and the rocker member which has been covering the port 42 will be moved, causing the port to be uncovered prior to the next up stroke of the piston and communication re-established with the cylinder recess 38. It will, therefore, be noted that the rocker member is adapted to pass over the port 42 for establishing and cutting off communication between the high pressure compartment 25 and recess 38, and thereby functioning as a valve controlled by the reciprocation of the blade 36.

Mounted upon the shaft 24 adjacent the end plate 32 is a fly wheel or counterweight 10. The end of the shaft and counterweight are preferably enclosed within the housing 71. The oil flowing through the axial passage 58 is delivered to the bearing of the plate 32, and to the thrust bearing 14 interposed therebetween and the counterweight 10. The end of the passage 58 is plugged, as at 75. The surplus oil on the bearing will be collected in the chamber 56 to be conducted therefrom by means of a tube 73 which has one end thereof located near the bottom of the chamber 56, and the other end extending through the housing 71 opening into the high pressure chamber 25. Due to the pressure of the compressed gas entering the chamber 56 the oil will be forced out ahead of the gas through the tube 73 into the compartment 25. The tube 73 is so positioned within the housing as to be able to drain nearly all of the oil that may collect therein during the operation of the compressor.

It will be apparent that lubricant is distributed to the various parts and bearings under force feed by the reciprocation of the blade or vane 36. Provided in the system is a sleeve valve 80 serving a dual purpose of maintaining a constant oil pressure and also as an unloading valve for relieving the compressor of work during the beginning of operations until sufficient speed is developed in the motor 16 to produce the required 75.

torque for operating the compressor. Referring to Figs. 5 and 6, oil is delivered from the axial passage 58 through a radial passage 59 to a passage 81 formed in the end plate 32. The cylinder block 30 is provided with a transverse bore 82 in which is disposed the sleeve valve 80, held against its seat 83 formed in the end plate 32, by a coiled spring 84. The spring 84 has one end thereof received in the sleeve of the valve and its other end bearing against the partition 28. A port 85 is formed in the seat 83 which forms a communication between the passage 81 and the bore 82. The bore is provided with a port 86 to allow the oil to return to the lubricant or high pressure compartment 25. The valve seat 83 is recessed or grooved, as at 87 to allow a permanent bleed or seepage around the valve 80 to permit its full return during the idle period of the compressor. When the compressor is operating at maximum speed the pressure in the system will be sufficient to move the sleeve 80 rearwardly against the spring 84, opening fully the port 86 for a complete cycling of the oil through the system.

Formed in the face of the cylindrical casting 30 is a groove 90 cooperating with the face of the partition 28 to form a passageway that opens into, at approximately near the top of the high compression compartment 25, and leads into the rear of the bore or cylinder 82. Drilled in the casting 30 is a passage 91 that opens into the cylinder 82 at a point rearwardly to the sleeve valve 80 when it is in abutment with its seat 83. The passage 91 communicates at its opposite end with a second passage 92 leading into the port 49 across the back side of the valve 48.

Before and during the initial starting period of the compressor, the sleeve valve 80 will be in abutment against its seat 83, permitting refrigerant to flow from the chamber 25 into the compression chamber 31, through the passage 90 into cylinder 82, entering passage 91, into 92, and to the inlet port 49. Thus the compressor is drawing the high pressure refrigerant, during the initial starting period, from the compartment 25 and discharging it back through the port 51, passage 55, past reed valve 52 into chamber 56, into the pipe 73 and out into the high pressure compartment 25, thereby accomplishing no work, merely permitting the motor 16 to gain its operating torque. As the speed of motor and compressor increases, the oil pressure rises until near the maximum speed the oil pressure will be sufficient to move rearwardly the sleeve valve 80 to cover the opening of the passageway 91, interrupting communication with the groove 90. Thereupon the compressor will draw the low pressure gaseous refrigerant from the evaporator 12 through the connection of conduit 13, opening 45, filtering chamber 46, passage 47, through check valve 48, into the port 49. The refrigerant after compression will be discharged through the already described route from exhaust port 51 into chamber 25. The pump blade 36 is so designed as to maintain a sufficient pressure of oil against the face of the sleeve valve 80 to hold it over the passage 91 during the operation of, or cycling of the refrigerating system.

The lubricant chamber 29 has communication with a chamber 95 formed in the end of the tubular bearing 23 by means of an oil duct 96 formed in the end plate 22. Surrounding the shaft 24 and located within the chamber 95, is a spring control expansive seal 97, one end of this seal being attached to a disk 98, interposed between

the end plate 22 and section 20, whereas the other end of the seal bears against a shoulder 99, formed on the shaft 24. A passage 100 communicates with chamber 95 and the suction port 49 to maintain the seal under low or suction pressure of the compressor.

A suitable packing 101 is mounted on the shaft 24 adjacent the end section 22 which packing is held in place by a coiled spring 102 encircling the shaft and bearing at one end against the pulley 11. This packing and sleeve functioning as a stuffing box to prevent the seepage of lubricant through the end section 22. Some of the oil collected in the chamber 95 of the bearing 23 is conducted therefrom through the passage 100 to the intake port 49 where it will commingle with the refrigerant as it passes the check valve 48. A baffle plate 103 permits only the overflow to pass down through the passage 100.

Although only a preferred form of the invention has been illustrated, and that form described in detail, it will be apparent to those skilled in the art that various modifications may be made therein without departing from the spirit of the invention or from the scope of the appended claims.

I claim:

1. In a compressor, comprising a cylinder having a compression chamber, a gyrating piston in said compression chamber, said cylinder provided with a passage having communication with the compression chamber, a piston blade mounted in said passage and adapted to be reciprocated in said passage by said piston in its movement in said chamber, said piston blade being provided with a lubricating passage lengthwise thereof, said cylinder having an oil inlet therein communicating with said cylinder passage and offset with respect to the vertical axis of the blade, and a rocker mounted in said cylinder passage and at one side of said blade to act as a valve for said oil inlet, said blade on one stroke drawing lubricant into the cylinder passage and on another stroke oscillating the rocker to close the oil inlet and allowing said blade to force the lubricant into the compressor.

2. In a compressor, comprising a cylinder having a compression chamber, a gyrating piston in said chamber, a shaft having an eccentric for operating the piston, said shaft and eccentric having lubricating passages in associated relation, a piston blade reciprocated by the movement of the piston and having a lubricant passage adapted to deliver lubricant to the passages of the shaft and eccentric, said cylinder having a passage in communication with said chamber and in which the piston blade reciprocates, said cylinder having an oil inlet communicating with said cylinder passage and offset with respect to the vertical axis of said blade, and a rocker mounted in said cylinder passage and at one side of said blade to act as a valve for said oil inlet, said blade on its up-stroke oscillating the rocker to open the inlet and allow lubricant to be drawn into the cylinder passage through said oil inlet by said piston blade and on its down stroke operating the rocker to close the oil inlet to permit said blade to force the lubricant in the cylinder passage through the passage of the blade and into the passages of the shaft and eccentric.

3. In a compressor, comprising a cylinder having a compression chamber and a gyrating piston in said chamber, a piston blade connected to the piston and adapted to be reciprocated in the

- travel of the piston, said cylinder having a recess in communication with said chamber, said cylinder having an oil inlet communicating with said recess for the admission of lubricant thereto and disposed laterally of the vertical axis of said piston blade, rockers mounted in said recess and between which rockers the piston blade reciprocates, one at least of the rockers functioning as a valve for said oil inlet, resilient means interposed between said rockers to prevent binding on the blade and for increasing the sealing pressure at their upper ends with the blade, said blade on its upstroke oscillating the rockers and permitting lubricant to be drawn into the recess and on its downstroke moving one of the rockers to close the oil inlet for cutting off the supply of lubricant to the recess and causing the confined lubricant to be ejected by said blade into the compressor.
5. The combination of a compressor including a cylinder and a gyrating piston, a piston blade adapted to be reciprocated in the travel of the piston, said cylinder having a passage in which the blade reciprocates, said passage provided with an oil inlet port for the admission of lubricant thereto, and a rocker member disposed along one side of the passage and blade for guiding the blade and acting as a valve for opening and closing said inlet port, said blade on its upstroke operating the rocker for opening the inlet port and allowing oil to be drawn into the passage and on the downstroke of the piston moving the rocker to close the oil port and permitting said blade to pump the oil out of said passage into the compressor. 5
6. The combination of a compressor including a cylinder having a compression chamber and a gyratory piston in said compression chamber, a piston blade connected to the piston and adapted to be reciprocated in the travel of the piston, said cylinder having an intake port and an outlet port leading to said compression chamber and disposed respectively on opposite sides of said piston blade, said cylinder having a recess in communication with the chamber, rockers mounted in said recess and between which the piston blade reciprocates and resilient means interposed between said rockers and beneath said piston blade to prevent the rockers binding on the blade and for increasing the sealing pressure at their upper end with the blade. 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520
